Primary Examiner — Cynthia R Underwood(74) *Attorney, Agent, or Firm* — Oliff PLC(57) **CLAIM**

The ornamental design for a climbing apparatus, as shown and described.

DESCRIPTION

FIG. 1 is a front, left-side perspective view of the climbing apparatus;

FIG. 2 is a front elevational view thereof, the rear elevational view (not provided) being a mirror-image thereof;

FIG. 3 is a top plan view thereof;

FIG. 4 is a left-side elevational view thereof;

FIG. 5 is a right-side elevational view thereof;

FIG. 6 is a bottom plan view thereof; and,

FIG. 7 is a rear elevational view thereof in an open configuration.

The broken lines depict unclaimed parts of the climbing apparatus, and thus form no part of the claimed design.
